Primary Examiner — Katie Jane Stofko*(74) Attorney, Agent, or Firm* — Akek IP, LLC

(57)

CLAIM

The ornamental design for a confection, as shown and described.

DESCRIPTION

FIG. 1 is a front, bottom and left side perspective view of a confection showing our new design;

FIG. 2 is a bottom plan view thereof;

FIG. 3 is a top plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The dash-dot lines in FIGS. 1-7 and the areas within the dash-dot lines shown in phantom show portions of the confection that form no part of the claimed design.

1 Claim, 5 Drawing Sheets(56)
